UNITED STATES PATENT OFFICE.

ALBERT W. LINN, OF MEMPHIS, TENNESSEE.

ADVERTISING APPARATUS.

1,298,977.

Specification of Letters Patent.

Patented Apr. 1, 1919.

Application filed October 25, 1916. Serial No. 127,608.

To all whom it may concern:

Be it known that I, ALBERT W. LINN, a citizen of the United States, and a resident of Memphis, in the county of Shelby and State of Tennessee, have invented certain new and useful Improvements in Advertising Apparatus; and I do hereby declare the following to be a full, clear, and exact description of the invention, such as will enable others skilled in the art to which it appertains to make and use the same.

This invention relates to an improvement in advertising and indicating apparatus of the type wherein portions of the two sides of the band carrying advertisements or other matter to be exhibited, are simultaneously exposed, whereby a plurality of advertisements, or a single advertisement made up of the matter on the two exposed portions of the band will be displayed.

The object of the invention is to provide an automatic advertising apparatus which will intermittently display the whole series of advertisement on the band, and then automatically reverse the direction of movement of the band and display the same advertisements in the reverse order, thus providing for the regular and continuous intermittent display of the whole series of advertisements, so long as the actuating motor is operating.

The invention consists in the parts and combinations of parts and in the details of construction as will be more fully explained and pointed out in the claims.

In the accompanying drawings;

Figure 1 is a view in elevation of my invention, part of the front being broken away to show the reversing mechanism; Fig. 2 is a view in transverse vertical section through the casing; Fig. 3 is a view of an end of the apparatus the front being removed; Fig. 4 is a view in section on the line 4—4 of Fig. 2; Figs. 5 and 6 are views of the pawl and ratchet mechanisms, Figs. 7 and 8 are views of the reversing mechanism, and Figs. 9 to 14 are views of detached parts of the reversing mechanism.

1 represents a box or casing having one or two openings in the front thereof through which the advertisements or other matter on the band 2 is displayed. In the present instance, I have shown two openings 3 and 4 which are preferably covered with glass, and through which the band 2 may be

viewed. The band 2 may be of any desired length, and is secured at one end to the winding roll 5, and at its other end to the winding roll 6. It passes from the upper winding roll 5 over idle roll 7 at the top of case 1, and then down in rear of opening 3 and under pinch roll 8; thence rearwardly toward the back of the case 1 where it passes over the idle roller 9, and downwardly under idle roll 10; forwardly under idle roll 11, up over pinch roll 12 and back to winding roll 6, the portion of the band between idle roll 11 and pinch roll 12 being exposed through the lower opening 4 of the case.

The lower pinch roll 12 is mounted on a shaft 13 which is provided at one end with mutilated or intermittent gear 14, through which power is applied to pinch roll 12, from the automatic reversing mechanism which will be hereinafter referred to.

Pinch roll 12 carries a gear wheel 15 meshing with a gear wheel 16 on pinch roll 8, and the gears on pinch roll 8 and 12 are geared up to gears 17 and 18 on winding rolls 5 and 6 respectively, by the intermediate gear wheels 19 and 20, so that when motion is imparted to pinch roll 12, rolls 8, 5 and 6 will be rotated in synchronism and operate to wind the band on one of the winding rolls and unwind it from the other.

The pinch rolls 8 and 12 rotate in synchronism and at the same rate of speed, and are sufficiently close together to prevent any slipping of the band between them, and may if necessary, be surfaced with rubber or other suitable material which will absolutely prevent any slipping, creeping or lagging of the parts of the band engaged thereby.

It is necessary however to provide for a differential movement of the winding rolls 5 and 6, as it is evident that if they were geared to the pinch rolls so as to rotate at the same speed therewith, the pull on the band would be gradually increased as the diameter of the winding roll increases, due to the winding of the band thereon, and would pull the portion of the band being wound, from between the pinch rolls, and in order to prevent this acceleration of speed and pull, and cause the band to be wound up at the speed it is fed to the winding rolls by the pinch rolls, I connect the gear wheels 17 and 18 to the said rolls 5 and 6 by friction or slip clutches which permit the

said rolls to slip or rotate independently of the shafts on which they are loosely mounted.

The friction or slip clutches on the shafts 5 of rolls 5 and 6 are alike hence a description of one will suffice for the other.

- The gear wheel 17 is fixed to the shaft of roll 5, and the latter is loosely mounted on said shaft. Located on the said shaft intermediate 10 said gear wheel and roll, is the collar 22 provided with a disk shaped flange 23, and between the latter and the gear wheel 17, is a friction disk 24 of leather or other suitable material. The collar 22 is provided 15 at its end adjacent the roll 5 with a ratchet wheel 25, which is engaged by a pawl 26 carried by the roll 5. Gear wheel 17 and flange 23 bear against the friction washer 24 with sufficient pressure to rotate the roll 20 5 when there is no opposition, but if the roll be winding the band, the clutch will permit the roll to slip on the shaft, so that it may take up the band only as it is fed by the pinch rolls and without any pulling action 25 25 which would tend to pull or draw the band faster than it is fed by the pinch rolls. The pawl and ratchet arrangement at this end of the shaft is for rotating the roll 5 in a direction to wind up the band thereon.
- 30 Mounted at the ends of the rolls 5 and 6 farthest removed from the friction clutches, are friction brakes which operate to prevent the said rolls 5 and 6 from unwinding the band faster than the latter is withdrawn 35 therefrom by the rotation of the pinch rolls. Each brake consists of a collar 27 loose on the roll shaft and provided with a disk shaped flange 28 which bears against a leather or other suitable friction washer located 40 between said flange and the end of the roll. The collar 27 is provided with a fixed ratchet wheel 29 which is engaged by the pawl 30 pivoted to the side frame of casing 1, and operates as a brake to hold the collar 45 27 and flange 28 against rotation while the band is being unwound from the roll, but permits the collar 27 and also the roll to rotate without opposition, in a direction to wind up the band thereon.
- 50 There is a clutch and brake for each roll 5 and 6, and the necessary tension or friction is applied to each clutch and brake by the thumb screws 29^a, which are screwed into threaded openings in the end of the 55 casing 1 and bear against the ends of the shafts. By forcing the shafts of rolls 5 and 6 longitudinally which will be done by tightening up the thumb screws 29^a, the friction members of the clutch and brake 60 will be forced into close contact with the rolls between them, thus increasing the power necessary to turn the rolls, and by loosening up on the thumb screws, the power necessary to turn the rolls will be lessened. 65 By carrying the band 2 around the rollers

as previously explained one face of the band will show through opening 3, and the opposite face through opening 4, thus permitting both sides of the band to be utilized. Each exposed part of the band may carry an advertisement complete, or a single advertisement, one portion of which is on one face of the band and the other portion on the other face may be simultaneously exposed through the two openings 3 and 4. The feeding of 70 the band in its two directions is done solely by the pinch rolls, the winding rolls operating merely to wind up at one end and unwind at the other and are, as before explained free to slip so that there will be no 80 pull on the band sufficient to overcome the pressure or feed of the pinch rolls. In winding, say, on roll 5 the latter will be rotated by its pawl and ratchet at the clutch end of the roll, the pawl at the brake end 85 of the roll, riding over its ratchet. As the band is being wound on the upper roll, it is being unwound from the lower roll 6, and during the unwinding movement of the lower roll, the brake collar of the latter is 90 held from rotating by its pawl and ratchet which latter operate to prevent any racing or other movement of the roll except that which is caused by the pull of the band. As the diameter of the lower roll with the band 95 thereon is greater than the diameter of the gear wheel, the roll with the band thereon necessarily moves slower than the gear wheel 18, and this difference in movement in the same direction between the roll and its gear 100 wheel is permitted by the ratchet and pawl connection between these parts.

The gear 14 on the shaft of the lower pinch roll, is mutilated so that it comes to a stop once at each rotation, thus stopping the 105 movement of the belt and permitting the advertisement on the exposed parts of the belt to be read. This gear 14 is engaged by a mutilated gear 30^a connected up with the reversing mechanism. This gear 30^a is considerably larger than gear wheel 14 and is provided with teeth sufficient to rotate gear wheel 14 once at each revolution, the remaining portion of the periphery of wheel 30^a being free of teeth, so that wheel 14 will 110 rotate only when engaged by the teeth of gear wheel 30^a, and will remain still during the travel of the mutilated surface of gear 30^a over the mutilated surface of gear 14.

31 is a main drive shaft adapted to be 115 coupled up to any suitable source of power, such as an electric motor. It is provided with a worm 32 which meshes with worm wheel 33 on shaft 34. Rigid with worm wheel 33 is the gear wheel 35 adapted 120 to mesh with either gear wheel 36 or 37, which latter are in mesh with each other, and gear wheel 37 is in mesh with gear wheel 38 which is keyed on shaft 30^b to which the mutilated gear 30^a is secured.

Gear wheels 36 and 37 are mounted on the short arm of an L-shaped tripping frame 39, which is mounted at its elbow on shaft 30^b, and is adapted to rock so as to bring either 5 gear 36 or 37 into mesh with gear wheel 35. When gear 36 is in mesh with gear wheel 35, shaft 30^b will be rotated in one direction and rotate pinch roll 12 in one direction, and when the tripping frame is tilted so as to 10 bring gear 37 into mesh with gear 35, and remove gear wheel 36 from contact with wheel 35, the movement of shaft 30^b will be in the reverse direction, so that by shifting the tripping frame from 15 one position to the other at regular intervals, motion will be imparted to the lower pinch roll 12 to unwind the band from one roll 5 or 6, and wind it on the other and then reverse its movement so as to unwind it from the 20 roll on which it was wound and wind it on the roll from which it was withdrawn.

Secured on shaft 30^b is the cam 40 located between the kickers 41, which latter are normally drawn toward each other by one or 25 more springs 42. Fixed to the cam 40 is the tooth or spur 42^a adapted to engage the teeth of the star wheel 43 and turn the latter one tooth at each complete revolution of the cam. Star wheel 43 is provided with a laterally 30 projecting tooth or spur 44 which engages the teeth of star wheel 45 and turns the latter one tooth with each revolution of star wheel 48. Star wheel 45 is provided with a laterally projecting tooth or spur 46 which engages 35 the swinging lever 47 once at each revolution of star wheel 45. Swinging lever 47 is carried on a pin 47^a carrying the pawls on the upright arm of the tripping frame 39, near the upper end of the latter and is 40 provided on one face with a rigid projection 48 which lies under the pawls 49 and 50. These pawls are adapted to engage the shoulders 51 for holding the tripping frame in its two positions. When pawl 49 is in 45 engagement with its shoulder 51, tripping frame 39 will be held in a position where gear 36 will engage driving gear 35, and when the tripping frame is shifted so as to bring the end of pawl 50 against its shoulder 51, gear 36 will have been moved out of 50 engagement with gear wheel 35 and gear wheel 37 moved into engagement with the same.

This swinging lever 47 as previously explained is pivotally mounted on the tripping frame 39 and lies in the path of movement of the tooth or spur 46 on star wheel 45, and is shifted at each revolution of the star wheel, and when so moved or shifted, the projection 48 thereon engaging the underside of one of the pawls 49 or 50 lifts the pawl thus leaving the frame 39 free to be shifted from one position to the other. It will of course be understood that with each 60 shift of the frame 39, the direction of rotation of the star wheel is reversed, so that the

shift or movement of the swinging lever 47 is always toward the pawl to be released.

After the tripping frame has been released it must be shifted and this is accomplished by the kickers 41. The kickers are 70 located on opposite sides of the cam 40, and are moved outwardly into set position by said cam, the latter operating to move or force the kicker outwardly against the tension of its spring. Each kicker is provided 75 at its upper end with pivoted arms 52, each of which is normally depressed by a spring 53. The kickers are forced outwardly or into operative position as previously explained by the cam 40, and are held in such 80 position by the engagement of the teeth 54 on the arms 52, with the shoulders 55 on a rigid part of the supporting frame. Each arm of the kicker has a depending swinging finger 56 adapted to be engaged by the 85 tooth or spur 46 of the star wheel 45, so that as the spur on the star wheel engages the finger, it lifts the same and also the arms 52, sufficiently to disengage the tooth 54 on arm 52 from its shoulder 55, thus leaving 90 the kicker free to be drawn inwardly or toward frame 39, by its spring. The spur 46 on the star wheel 45 also shifts the swinging lever 47 once at each revolution or part 95 revolution of the wheel, and the projection 48 on the latter disengages one of the pawls 49 or 50 thus leaving the tripping frame 39 free to be shifted. After the kicker has been released as above explained it is drawn inwardly by its spring and its free end striking 100 against the pin 47^a on the tripping frame shifts the latter to its other position where it is held by its pawl 49 or 50, until again released by the spur 46 on star 105 wheel 45.

This shift of the lever 39 causes a reversal of the direction of rotation of all the parts intermediate gear wheel 35 and pinch roller 12, and consequently a reversal in the direction of movement of the band 2 and this 110 reversal takes place at regular intervals so long as the drive motor is running.

The upper star wheel 45 does not make a complete rotation, but rocks back and forth by the reversal of the direction of movement 115 of the lower star wheel 43, hence by changing the position of the spur or spurs on one or both of these wheels, the movement of the band can be regulated so as to be reversed immediately after the display of the last 120 advertisement on the same, and the adjustment can be such as to provide for the display of any number of advertisements, and the reversal of the band immediately after the display of the last one. Cam 40, with 125 the spur 42^a thereon, makes ten revolutions to every single revolution of wheel 43, and the latter makes ten revolutions to every one of wheel 45, so that each machine, with the construction as illustrated, will provide 130

for one hundred advertisements which number can be increased or diminished by increasing or diminishing the number of teeth on wheels 43 and 45. Where only one pin 5 or spur wheel 46 is used on wheel 45, the latter will make approximately one revolution, the single spur 46 by its contact against the opposite sides of the swinging lever 47 shifting the same in a direction to release a pawl, 10 thus leaving the tripping frame 39 free to be shifted by a kicker 41, which has previously been released by the movement of the spur 46. If however the machine has less advertisements than its capacity, say only 15 fifty, wheel 45 will be provided with two pins located diametrically opposite, and will therefore operate to reverse at each half revolution. In Fig. 13 I have shown wheel 45 with three extra holes into any one of 20 which the second pin may be placed.

It is evident that my improved apparatus may be used as a street or station indicator by merely substituting the name of streets or stations in its upper part for advertising 25 matter or in addition to the advertising matter, and it is also evident that the advertising or indicating data to be displayed by the apparatus be varied as may be desired without departing from the spirit of my 30 invention.

It is evident that many slight changes might be resorted to in the relative arrangement of parts shown and described without departing from the spirit and scope of my 35 invention. Hence I would have it understood that I do not wish to confine myself to the exact construction and arrangement of parts shown and described, but consider myself at liberty to make such changes as 40 fairly come within the spirit and scope of my invention.

Having fully described my invention what I claim as new and desire to secure by Letters-Patent, is:—

45 1. In an advertising device the combination of a band, winding rolls to which the ends of the band are secured, two positively driven push rolls intermediate the winding rolls and between which two thicknesses of 50 the band pass so that both faces of the band will be exposed at the front, and slip gearing connecting the pinch rolls and winding rolls whereby the latter are free to slip so as to take up the band as it is fed to the 55 latter from the pinch roll.

2. In an advertising device the combination of a band, winding rolls to which the ends of the band are secured, two positively driven pinch rolls intermediate the winding 60 rolls and between which two thicknesses of the band pass so that both faces of the band will be exposed at the front, gearing between the pinch rolls and winding rolls shafts, and friction brake mechanism acting

against the winding rolls for controlling the 65 unwinding movement of the latter.

3. In an advertising device the combination of a band, winding rolls to which the ends of the band are secured, two positively driven pinch rolls intermediate the winding 70 rolls and between which two thicknesses of the band pass so that both faces of the latter will be exposed at the front, slip gearing connecting the pinch and winding rolls whereby the latter will be free to slip so as 75 to take up the band as it is fed from the pinch rolls, and friction brake device engaging each winding roll for controlling the unwinding movement of the latter.

4. In an advertising device, the combination of a casing having an open face, two positively driven pinch rolls located intermediate the upper and lower ends of the opening in the face, an idle roll at the upper end of the opening, an idle roller at the lower end of the opening, two winding rolls located in a plane to the rear of the pinch rolls, a band secured at its ends to said winding rolls, the said band being so disposed with relation to the rolls, that a double thickness of belt passes between the pinch rolls, one thickness of belt passing over the upper idle roll and the other under the lower idle roll, a drive shaft, and reversing mechanism located intermediate the drive shaft and the driven pinch roll whereby the direction of movement of the belt will be reversed at regular intervals. 90

5. The combination with a driving gear, a tripping frame carrying intermeshing gears 100 either of which may be moved into mesh with said driving gear, a gear wheel in mesh with one of said gears on the tripping frame, and driven thereby, pawls for holding the tripping frame in its two positions and automatically actuated means for disengaging the holding pawl so as to permit the tripping frame to be shifted. 105

6. The combination with a driving gear, a tripping frame carrying intermeshing gears 110 either of which may be moved into mesh with said driving gear, a gear wheel in mesh with one of said gears on the tripping frame, two kickers for shifting the tripping frame and automatic means for actuating the 115 kickers.

7. The combination of a driving gear, a tripping frame, carrying intermeshing gears either of which may be moved into mesh with said driving gear, pawls for holding 120 said frame in its two positions and means for releasing the said pawls, and means for shifting the frame, the said means being actuated automatically by the gearing.

8. The combination of a driving gear, a 125 tripping frame carrying intermeshing gears either of which may be moved into mesh with said driving gear, pawls for holding

said frame in either of its two positions, spring actuated kickers for shifting the frame from one position to the other, and means actuated by said gearing for releasing the pawls and for freeing the kickers so as to permit the latter to shift the frame.

5 In testimony whereof, I have signed this

specification in the presence of two subscribing witnesses.

ALBERT W. LINN.
